United States Patent Office

Des. 178,079

Patented June 19, 1956

178,079

ELECTRIC BEDCOVERING CONTROL UNIT

Carl Otto, New York, N. Y., assignor to Bobrich Products
Corp., New York, N. Y., a corporation of New Jersey

Application August 22, 1955, Serial No. 37,611

Term of patent 7 years

(Cl. D26—1)

Fig. 1.

Fig. 2.

Fig. 3.

Fig. 1 is a plan view of an electric bedcovering control unit, showing my new design.

Fig. 2 is a side view thereof.

Fig. 3 is a front view thereof.

The dominant feature of the design resides in the portion shown in full lines.

I claim:

The ornamental design for an electric bedcovering control unit, substantially as shown and described.
